John Rogers.
N° 1,598. Design for Statuary. (The Town Pump.)
Patented May 27, 1862.

Nancy A. Lord
Jos. R. Brewster

John Rogers

Res. 1598

John Rogers, of New York, N. Y.
Letters Patent No. 1598 - dated May 27, 1862.

The schedule referred to in these Letters Patent and machinery part of the name.

Dec. 1598

To all whom it may concern:

Be it known that I, John Rogers, of the City and State of New York, have invented or produced a new and original design for a group of Statuary, and I do hereby declare that the following is a full and exact description of the same. The group is called *The Town Pump*, and consists of two figures A and B, conversing by the pump C.

The figure A, stands with his left foot D, on the ground E, his right foot F, is on the top of the trough G. His right arm H, rests on the top of the pump C. In his left hand I, he holds his drinking cup J. He is dressed in an overcoat K, and has on his knapsack L. His canteen M, and haversack N, hang by his side. He is looking towards his companion B, who has a pail O, on her right arm P, and is playing with the end of her shawl Q, which she wears over her head.

Her dress R, is caught up showing her skirt S, below.

Having thus described my invention, what I claim and desire to secure by Letters Patent, is a design for a group of Statuary, as herein fully described and shown.
